UNITED STATES PATENT OFFICE.

JOHN L. WHITEHURST, OF BALTIMORE, MARYLAND, ASSIGNOR, BY MESNE ASSIGNMENTS, TO JOHN T. WHITEHURST, OF BALTIMORE, MARYLAND.

LABELING-MACHINE.

1,329,260.

Specification of Letters Patent. Patented Jan. 27, 1920.

Application filed August 30, 1915. Serial No. 47,921.

To all whom it may concern:

Be it known that I, JOHN L. WHITEHURST, a citizen of the United States of America, and resident of Baltimore, Maryland, have invented certain Improvements 5 in Labeling-Machines, of which the following is a specification.

This invention relates to a labeling machine whereby a can of a given diameter 10 may be provided with a label which extends entirely around its body and has its ends lapped as is commonly done, or a shorter label which covers only a portion of the circumference of the can, and is secured there- 15 to by an adhesive which is applied to the can in two places, thus obviating the necessity of employing two separate machines, as will hereinafter fully appear.

In the description of the said invention 20 which follows, reference is made to the accompanying drawings, forming a part hereof, and in which:—

Figure 1 is an exterior side view of such parts of the machine as are involved in the 25 present invention; and Fig. 2 a sectional plan of Fig. 1, taken on the broken line $x-x$.

Fig. 3 is an end view of two cans one of 30 which is shown as provided with a long, and the other with a short label.

Referring now to the drawings, 1, 1 are bars which constitute the main portion of the frame of the machine, and 2, 2 standards best shown in Fig. 1, at the entrance end of 35 the machine which standards support the shaft 3 upon which are secured pulleys 4 carrying belts 5 which rotate the cans to be labeled, and roll them longitudinally of the machine to its delivery end. A can de- 40 noted by 7 is shown in dotted lines in Fig. 1.

10 is a columnar stand which supports the bars 1 of the frame of the machine, and 12 the label table secured to the top of the bar 13 which extends downward in the columnar 45 stand, and is provided with spring devices, not shown, which serve to keep the upper label of a stack of labels, in the path of the rolling cans, as is common in machines of this class.

50 15 is the guide and stop for the forward end of the stack of labels and is adjustable so that it can be placed at a proper distance from the main adhesive-applying devices which consist of a pot 17 which contains an

adhesive, preferably a substance which is 55 liquefied by heat, and a system of rotary disks 20 partially immersed in the adhesive and which in their rotation apply the adhesive to the cans as they are rolled over them. 60

21, 21 are the track rails along which the cans are rolled, and 23 is a clamping device and stop from under which the rear end of the upper label of the stack of labels is drawn, when the labels are of such length as 65 to envelop the entire circumference of the cans.

24, 24 are the side guide rails which keep the cans centrally of the machine as they traverse the bed toward the delivery end of 70 the same.

The machine so far described will be recognized by those skilled in the art as one commonly in use; and the devices whereby the machine is adapted to apply shorter 75 labels, or labels which cover only a portion of the circumference of the body of the cans, will now be described.

It will be understood that the main adhesive applying devices which as before 80 stated consist of the cement pot 17 and the rotary disks 20, are given a position with respect to the label table 12 and the guide 15 for the stack of labels.

25 is a second cement pot provided with 85 disks 27, corresponding in all essential particulars with those before described. 30 is a stop bar for the rear end of the stack of short labels, which is dependent from a bar 32 the ends of which rest in depressions in 90 the bars 1 and are temporarily held to the said bars by screws c .

The movable paste pot 17 and the end stop 23 are the principal factors in the application of the long or full length labels, 95 and with these devices the usual transverse pasting belt, not shown, is used. When half length labels are employed this lap pasting belt is discarded, and cement applied in such manner that the labels shall be held at each 100 end. Under such conditions, the fixed cement pot 25 is used in connection with the stop 32, it being understood that when full length labels are employed this stop is to be detached. The rod 30 extends from the 105 stop 32, the former being narrow, so that it readily may fit in the space incident to the two-piece label table, as will be clear to

those familiar with the art. The stop 32 practically has the function of the front stop 15, both serving to fit the labels in their correct position on the table.

- 5 Suppose the machine to be in the condition shown in the drawings, and short labels are to be applied to cans, the labels are stacked on the table, both cement pots being in the position indicated and provided with the adhesive. The second cement pot 25 with its disks 27 is supposed to have been given the proper longitudinal adjustment with respect to the cement pot 17 the position of which is unchangeable. Further, let it be supposed that the devices which apply paste to the rear end of the long labels have been removed or rendered inoperative.

The machine being in motion, cans entering the machine and rolling over the cement 20 applying disks 20 and 27 receive dabs of cement in two places which are circumferentially separated a distance practically equal to the length of the labels to be applied, and after the labels are picked up, the cans pass 25 to the appliances which smooth the labels upon the cans and which are commonly in use in labeling machines, and are discharged.

Should it now be required to change the machine so as to apply long labels or those 30 which extend entirely around the can bodies, it is only necessary to put the second cementing appliances out of service which can easily be done by unshipping the belt which drives the pulley 35, removing the stop bar 35 30, and resuming the action of the transverse pasting belt, not shown, when the operation of the machine is the same as that of labeling machines now commonly in use.

I claim as my invention:

- 40 1. In a labeling machine, a bed, means to roll cans longitudinally of the bed from the entrance to the delivery end of the same, a table to hold a stack of labels, a pair of separated adhesive-applying devices situated at 45 the entrance end of the bed, whereby a can in rolling over the said separated devices shall receive two applications of cement before reaching said table, and a removable

depending stop bar adapted for use with short or half length labels.

50

2. In a labeling machine, a bed, means to roll cans along the bed from the entrance to the delivery end of the same, adhesive-applying devices situated near the entrance end of the bed, a label table, other adhesive-applying devices situated between the first devices and said table, whereby the cans shall receive two applications of adhesive before reaching the labels on the table, and a removable depending stop bar adapted for 60 use with short or half length labels.

55

3. In a labeling machine, a bed, means to roll a can longitudinally of the bed from the entrance to the delivery end of the same, a table to hold a stack of labels to be applied to cans, adhesive-applying rollers situated at the entrance end of the bed, a second set of adhesive-applying rollers so situated between the first set and the table for holding the labels, whereby a rolling 70 can may receive two separate applications of adhesive before performing a full rotation, and a removable depending stop bar adapted for use with short or half length labels.

65

4. In a labeling machine, a bed, means to roll cans longitudinally of the bed from the entrance to the delivery end of the same, a table to hold a stack of labels, an adjustable adhesive applying device at the entrance end of the bed, an optionally operative or inoperative adhesive applying device in alignment with the said adjustable device capable of longitudinal adjustment with respect thereto, whereby when said adjustable device is operatively employed a can in rolling 85 over the said separated devices may receive two applications of cement at a predetermined distance apart less than the circumference of the can, and a removable depending stop bar adapted for use with short or 90 half length labels.
